UNITED STATES PATENT OFFICE

146,301

DESIGN FOR A CIGARETTE HOLDER

Earl H. Cooper, Chicago, Ill.

Application December 11, 1945, Serial No. 124,605

Term of patent 3½ years

(Cl. D85—8)

To all whom it may concern:

Be it known that I, Earl H. Cooper, a citizen of the United States, residing at Chicago, in the county of Cook and State of Illinois, have invented a new, original, and ornamental Design for a Cigarette Holder, of which the following is a specification, reference being had to the accompanying drawing, forming a part thereof.

Fig. 1 is a perspective view of a cigarette holder showing my new design,

Fig. 2 is an end view looking at the mouthpiece thereof,

Fig. 3 is an end view looking at the cigarette holding end thereof; and

Fig. 4 is a sectional view taken substantially on the lines 4—4 of Fig. 1.

I claim:

The ornamental design for a cigarette holder, substantially as shown.

EARL H. COOPER.
